UNITED STATES PATENT OFFICE

WILLIAM A. H. WELLS, OF EDGEWOOD, RHODE ISLAND

DESIGN FOR A SERVING DEVICE FOR A PORTION OF CITROUS FRUIT

Application filed October 10, 1931. Serial No. 41,360. Term of patent 14 years.

To all whom it may concern:

Be it known that I, WILLIAM A. H. WELLS, a citizen of the United States of America, residing in Edgewood, county of Providence, State of Rhode Island, have invented a new, original, and ornamental Design for a Serving Device for a Portion of a Citrus Fruit, of which the following is a specification, reference being had to the accompanying drawings, forming a part thereof.

Fig. 1 is a top plan view of a serving device for a portion of a citrus fruit showing my new design; and Fig. 2 is an edge elevation of the same.

I claim:

The ornamental design for a serving device for a portion of a citrus fruit, substantially as shown.

WILLIAM A. H. WELLS.
